PATENTED APR. 24, 1906.

W. F. WEGNER.
ELECTRIC HAMMER.
APPLICATION FILED SEPT. 9, 1905.

UNITED STATES PATENT OFFICE.

WILLIAM F. WEGNER, OF NEW YORK, N. Y., ASSIGNOR OF ONE-HALF TO
ALEX WENDELBURG, OF NEW YORK, N. Y.

ELECTRIC HAMMER.

No. 818,589.

Specification of Letters Patent. Patented April 24, 1906.

Application filed September 9, 1905. Serial No. 277,708.

To all whom it may concern:

Be it known that I, WILLIAM F. WEGNER, a citizen of the United States, and a resident of the borough of Manhattan, in the city and State of New York, have invented a new and useful Improvement in Electric Hammers, of which the following is a specification.

My invention relates to an improvement in electric hammers, the object being to simplify the structure and render the hammer efficient for general use.

A practical embodiment of my invention is represented in the accompanying drawings, in which—

15 Figure 1 is a view of the hammer in longitudinal section, showing a tool in position therein; and Fig. 2 is a diagrammatical view showing the electrical connections for energizing and deenergizing the coils.

20 The hammer proper is denoted by 1. It is of a general oblong cylindrical shape and provided with deep sockets in its opposite ends, the one for receiving the reduced end of the tool-shank and the other for receiving a cushioning-spring, as will be hereinafter more particularly described.

25 The socket for receiving the reduced end of the tool-shank is denoted by 2, and that for receiving the cushioning and retraction 30 spring by 3.

The hammer proper, 1, is intended to reciprocate longitudinally within a tubular casing 4, about which are located two electro-magnetic coils 5 and 6, the coil 6 being wound 35 in a reverse direction from that in which the coil 5 is wound—for instance, if the coil 5 be wound right hand, the coil 6 is wound left hand. These coils 5 and 6 are in turn surrounded by a tubular casing 7, into one end 40 of which is fitted a tool-holder 8.

The tool-holder 8 is provided with a bore 9 for the reception of the tool-shank 10, the tool in the present instance being what is known in the art as a "chipper."

45 The shank 10 is extended in reduced form, as shown at 11, for the purpose of entering the socket 2 in the end of the hammer proper, 1, and in the bottom of the said socket there is welded or otherwise fixed a wearing-button 50 12, of hardened steel or other suitable blow-resisting material, which button forms a permanent part of the hammer proper. The reduced portion 11 of the tool-shank has its end

hardened so as to coact with the wearing-button in the hammer proper.

55 On the opposite end of the casing 7 there is screwed a handle 13, the said handle being provided with a hollow shank 14, screw-threaded on its interior for engaging the exterior screw-threads on the casing 7.

60 Within the hollow shank 14 on the handle I locate a follower 15, consisting in the present instance of a bronze plate, provided with a hollow boss 16, projecting from its face and bearing against the insulating-ring 17 at the 65 end of the coil 6. Within the hollow boss 16 there also projects from the plate 15 a prong 18, around which the cushioning and retracting spring 19 is seated. The spring 19 is gradually tapered as it extends toward the 70 hammer proper, 1, and its smaller end enters within the tapered socket 3.

75 In proximity to the plate 15 and exterior thereto I locate a disk 20, of insulating material, in the face of which contact-rings 21 and 22 are secured and also a central contact-plate 23. Outside of the disk 20 I locate a companion disk of insulating material 24, having on its face contact-rings 25 26 in position to register with the rings 21 22, respectively, and also a central contact-button 27 in position to register with the central plate 23. The disk 24 engages a shoulder 28 on the handle, and when the latter is screwed onto the casing 7 it forces the disk 24 against 80 the disk 20 and in turn forces the follower-plate 15 toward the coils, thereby pressing the coils endwise against the inner end of the tool-holder 8 and holding them securely in position against any liability of rattling or 85 displacement.

90 The handle 13 is hollow and has within its hollow chamber a bridge-piece 30, carrying binding-posts 31 and 32, the latter being in electrical communication with spring contact-plates 33 34, projecting parallel with the axis of the handle along the opposite sides of a stop-pin 35, set centrally in the bridge-piece 30. The handle is further provided with a push-button 36, seated in and projecting 100 from its end in position to receive the thumb or finger of the operator and capable of reciprocating within a socket 37, formed in the end of the handle in alinement with the hollow chamber 29 within the handle and communicating therewith through a contracted 105

neck 38. The push-button 36 has a contracted stem 39, which enters the end of a tubular plunger 40, fitted to reciprocate within the neck 38. The tubular plunger 40, of insulating material, carries a subplunger or contact-support 41, the contracted neck 42 of which reciprocates within a hole 43 in the end of the hollow plunger 40. The contracted stem 42 has an annular shoulder 44 or cap at its outer end, and between this cap and the end of the hollow plunger 40 there is located a spring 45. There is also a spring 46 located between the inner face of the push-button 36 and the inner end of the socket 37, in which the push-button works. The subplunger or contact-support 41 has fixed thereon two spring-contacts 47 and 48, so arranged as to engage with a close sliding contact, the contacts 34 and 33, respectively, when the push-button 36 is forced inwardly.

The manner in which the electrical connections are made will be understood by reference to the diagram Fig. 2, where 49 represents conventionally any suitable generator 25 and 50 a commutator provided with an insulated segment 51, the switch which has been described in detail hereinabove as located within the handle being shown conventionally at 52 and the contact-rings in the insulating-piece 20 being indicated by the numerals 21, 22, and 23, as in Fig. 1, it being understood that their corresponding contact-pieces in the disk 24 communicate with wires to the switch within the handle and to the commutator exterior to the handle, the said wires passing from the disk 24 along a conduit 52* within the handle to the chamber 29 and thence through an opening 53 in the cap-piece 54 at the end of the handle opposite the push-button 36. The positive pole of the coil 5 is connected by a wire 55 with the contact-ring 22 and thence by wire 56 to one of the brushes 57 on the commutator. The positive pole of the coil 6 is connected by a wire 58 with the contact-ring 21 and thence by a wire 59 to the other brush 58* on the commutator. The negative poles of both coils 5 and 6 are connected by a wire 60 with the contact-plate 23 and thence by a wire 61 30 with the binding-post 32 within the handle, thence through the switch to the binding-post 31, thence along wire 62 to one pole 63 of the generator, and from the opposite pole 64 of the generator by a wire 65 with the axis 55 of the commutator 50.

It is assumed that the commutator 50 has a rotary motion imparted to it in any well-known or approved manner and with such speed as may be required to impart to the 60 hammer the necessary number of impulses per minute.

In operation, assuming the parts to be in the position shown in Fig. 1, the coil 6 is energized, tending to draw the hammer proper, 65 1, back toward the handle. As soon as the

hammer is drawn back the commutator 50 will have rotated into position to bring the brush 58* on the insulated portion 51 and throw the brush 57 into contact to establish circuit through the wire and ring 22 with wire 55, thereby energizing the coil 5 and causing the hammer proper, 1, to advance and deliver its blow on the reduced portion 11 of the tool-shank. As soon as the blow is delivered the commutator will again have cut 70 in the circuit through the coil 6, energizing it and causing a withdrawal of the hammer from the tool. The moment the coil 6 is energized because of its being wound in the opposite direction from the coil 5 it will reverse 80 the polarity in the hammer 1 from that induced by the coil 5 and in so doing will set up between the shank of the tool and the hammer proper a repulsion which will cause the hammer to not only leave the tool-shank, but 85 be repelled therefrom. This action upon the tool-shank is emphasized by causing the hammer, which is made of material highly susceptible to magnetic influence, to surround the tool-shank for a considerable distance, 90 the tool-shank itself being also of material highly susceptible to magnetic influence save only its hardened end. By hardening the end of the tool-shank it is caused to momentarily hold the magnetism, thus facilitating 95 the operation of the tool.

The action of the switch within the handle is as follows: When the push-button is pressed inwardly, it carries with it the plunger 40 and the subplunger 41, closing the contact-pieces 34 33 and completing the circuit for starting the hammer. When pressure is removed from the push-button 36, its actuating-spring 46 will force it outwardly, the early part of its movement being idle as far as the subplunger 41 is concerned, as it is intended that the friction between the contact-pieces shall be sufficient to more than equal the tension of the spring 45 when in its expanded position. As soon, however, as the spring 45 105 has been compressed sufficiently to overcome the friction between the contact-pieces the contact-pieces 47 and 48 will begin to slide on the pieces 34 and 33, and this motion once begun will be completed with great celerity 115 by the action of the spring 45, which will throw the subplunger, with its contact-pieces, promptly away from the contact 34 33. This effectually prevents the burning out of the contacts and also serves to promptly 120 stop the hammer, and so economize energy.

It is obvious that changes might be resorted to in the form and arrangement of the several parts without departing from the spirit and scope of my invention. Hence I do not 125 wish to limit myself strictly to the structure herein shown and described; but

What I claim is—

1. An electric hammer comprising successive coils wound in opposite directions, a 130

- hammer proper arranged to reciprocate within the coils, a tool having its shank projected within the hammer and means for energizing and deenergizing the coils.
2. An electric hammer comprising successive coils wound in opposite directions, a hammer proper arranged to reciprocate within the coils, and provided with a socket in its end for receiving a tool-shank and means for energizing and deenergizing the coils.
3. An electric hammer comprising successive coils wound in opposite directions, a hammer proper arranged to reciprocate within the coils and provided with sockets in its opposite ends, one for receiving a tool-actuating stem or shank and one for receiving a spring, a spring arranged to enter said socket in one end of the hammer and means for energizing and deenergizing the coils.
4. An electric hammer comprising successive coils wound in opposite directions, a hammer proper arranged to reciprocate within the coils and provided with a socket for receiving a tool-shank, a wearing-button located in said socket, a tool-shank arranged to enter the socket and provided with a hardened end to receive the impact of the hammer and for momentarily holding the magnetism and means for energizing and deenergizing the coils.
5. An electric hammer comprising successive coils wound in opposite directions, a casing for the coils, a tool-holder engaged with the casing at one end, a handle engaged with the casing at the opposite end, a follower of non-magnetic material interposed between the handle and coils, a hammer proper arranged to reciprocate within the coils and provided with a socket in its end to-
- ward the handle, a spring guided by the follower and entering the said socket on the hammer and means for energizing and deenergizing the coils.
6. An electric hammer comprising successive coils wound in opposite directions, a suitable casing for the coils, a hollow handle engaged with the casing, disks of insulating material located between the handle and coils and provided with registering contact-rings, wires leading from the coils to the rings in one disk, wires leading from the companion disk through the handle, a commutator and source of electric energy for energizing and deenergizing the coils.
7. An electric hammer comprising a plurality of coils suitably arranged within a casing, a hammer proper arranged to reciprocate within the coils, a hollow handle attached to the casing, an electric switch located within the handle, said switch comprising a spring-actuated plunger under the control of the operator and a spring-actuated subplunger carried by the said plunger, a source of electric energy and contact-pieces within the handle in position to be connected and disconnected by the subplunger, said contact-pieces being connected the one with the coils and the other with a source of electric energy.

In testimony that I claim the foregoing as my invention I have signed my name in presence of two witnesses this 7th day of September, 1905.

WILLIAM F. WEGNER.
